UNITED STATES PATENT OFFICE.

JOHN DAVIS MANN, OF PETERSTOWN, WEST VIRGINIA.

QUILTING-MACHINE FRAME.

1,186,814.

Specification of Letters Patent. Patented June 13, 1916.

Application filed October 1, 1915. Serial No. 53,629.

To all whom it may concern:

Be it known that I, JOHN D. MANN, a citizen of the United States, residing at Peters-
town, in the county of Monroe and State of
5 West Virginia, have invented certain new
and useful Improvements in Quilting-Ma-
chine Frames, of which the following is a
specification, reference being had therein to
the accompanying drawing.

10 My invention relates to an improvement
in quilting machine frames, more particu-
larly in the type of quilting machine frames
that are suspended and used in connection
with a sewing or quilting machine.

15 The object of my invention is to provide
a collapsible frame for quilting machines
which is simple in structure, easily assem-
bled and taken apart and cheaply manufac-
tured.

20 Another object of my invention is the pro-
vision of an improved carrying structure
having novel assembled parts and adjust-
able characteristics.

25 Still further objects and advantages of
my structure will be ascertained from the
following description of the structure of
my frame to which reference is also made
in the accompanying drawings, Figure 1
30 of which represents a front elevation of the
frame in its suspended position. Fig. 2 of
which represents a side elevation of the
frame in its suspended position. Figs. 3, 4
and 5 show detail views of the structure.

Referring to the drawings A—A design-
35 nate the two end or side bars of the frame.
Extending transversely between these bars
are located the rollers B on which the ma-
terial to be quilted is carried; the arrange-
ment and structure of these rollers does not
40 differ from that used in former devices of
this character. One is placed at one end
of the side bars which roller receives the
upper and lower pieces of fabric after the
same have been quilted, and two similar
45 rollers are placed one at the other end of
the side bars on which one is rolled a sheet
of fabric forming one side of the material
to be quilted, and the other closely alongside
thereof from which is rolled a sheet of
50 fabric forming the opposite side of the ma-
terial to be quilted, but with sufficient space
intervening for the passage of the batting
or filling material. The ends of these roll-
ers are provided with suitable trunnions b,
55 which rest in grooves a. These trunnions
are formed with an enlarged head α having

close engagement with the outside of the
side bars. The grooves in which the trun-
nions rest are lined with suitable bushing
metal c, which prevents wearing of the 60
grooves.

Springs y are associated with the openings
of the groove which insures the trunnions
on the rollers being held in the grooves with-
out danger of slipping or working there-
from. I provide flanges or circular plates d
65 at the ends of the rollers and having close
association with the inner surface of the side
bars, these plates have a series of perfora-
tions e arranged circumferentially thereof 70
into which enter locking means e' suitably
secured to the side bars.

The advantage of having the heads of
the trunnions and the flanges closely asso-
ciated with the outer and inner surfaces 75
of the side bars, is that there is the same dis-
tance between the heads of the trunnions
and the flanges as the width of the side
bars, and the close fit of the same holds the
side bars rigid and prevents wearing and 80
twisting.

Mounted on the side bars are uprights C
provided at their ends adjacent the side bars
with U shaped yokes g which embrace the
side bars and allow for the longitudinal ad-
justment of the uprights on the bars where-
by the frame may be kept on an operative 85
plane regardless of the amount of material
on either of the rollers. Suitable locking
means for the uprights in their adjusted po-
sition are used, conveniently a longitudinal
series of perforations h are formed in the
side bars A and pins j are employed which
are capable of being inserted in any of said
perforations whereby the uprights C are 90
locked against movement on the side bars.
Besides being adjustable so as to keep the
frame in relatively the same plane as the
amount of material increases or decreases
on the rollers, these uprights, together with 100
the horizontal cross bar D, hereinafter de-
scribed, serve other purposes namely, they
hold the side bars A properly and rigidly
spaced apart. A distinct advantage is in
this as when any one or all of the rollers are 105
withdrawn to receive additional material
the side bars will remain in the same or prac-
tically the same position as when the rollers
were in position on the frame, and therefore,
the collapse of the frame when the rollers 110
are withdrawn is guarded against.

Suitably mounted on the uprights C is the

cross bar D of practically the same construction as the side bars, provided with yokes *k* which embrace the uprights and allow for the vertical adjustment of the cross bar with respect to the uprights. This cross bar is adjustably held against movement by pins *m* insertible in perforations *n* in the uprights. The object of the adjustment of this cross bar is that the frame can be raised and lowered to approximately any position with respect to the quilting or sewing machine.

The cross bar D has mounted thereon preferably an eye *o* to which is attached the suspending means of the frame. This suspending means consists, conveniently of a traveling block *p* mounted on wires attached to the walls of the room or place where the frame is to be used. By this means the movement of the whole frame along the wire is effected.

In operation when the amount of material increases on the receiving roller the frame has a tendency to tilt, when this tilt is apparent to the operator it is merely necessary to remove the pins from the perforations wherein they are located, slide the uprights toward the other end of the side bars until the frame assumes an operative or normal horizontal position. The uprights are then locked in their adjusted position by inserting the pins in the perforations that have the closest proximity to the yokes attached to the uprights.

When any of the rollers are withdrawn it will be apparent that the side bars will be held in their normal position by the rigidity of the uprights and cross bar.

When during the quilting operation it is desired to raise or lower the frame with relation to the quilting machine it is merely necessary to remove the pins from their location in the perforations in the uprights, which allows the cross bar to be vertically adjusted on the uprights where it may be

locked in its adjusted position by inserting the pins in the perforations having the closest proximity to the yokes above the cross bar.

It will be readily seen that minor changes may be made in the construction of my quilting machine frame without departing from the scope or spirit of my invention.

What I claim is:

1. In a quilting machine frame, the combination with parallel side bars having inclined trunnion receiving grooves in their upper faces at opposite ends, rollers having trunnions fitted in said grooves, springs overhanging the grooves, for normally retaining the trunnions in place, upright supports intermediate the ends of the bars, means for adjustably positioning the supports at different points on the side bars and for retaining the same in said adjusted position, a cross bar connecting the supports and a flexible support connected centrally to the cross bar.

2. In a quilting machine frame the combination with side bars having trunnion receiving obliquely arranged metal lined grooves at opposite ends, rollers having trunnions fitting the grooves, each trunnion being provided with a head arranged to engage the side of the side bars, with movable means overlapping the grooves for retaining the rollers in place, adjustable uprights secured to the side bars intermediate their ends, securing pins for maintaining the uprights in different positions of adjustments on the side bars, a rigid connecting bar between the upper ends of the uprights, and a flexible support connected to the connecting bar.

In testimony whereof I hereunto affix my signature in the presence of two witnesses.

JOHN DAVIS MANN.

Witnesses:
